PROJECTILE

Stephen A. Moore, Roanoke, Va.

Application August 26, 1943, Serial No. 500,122

2 Claims. (Cl. 102—50)

My invention relates to projectiles fired from cannon and similar pieces of ordnance, and has among its objects and advantages the provision of an improved glider projectile so designed as to cause the projectile to travel an increased distance as it reaches the descending stretch of the trajectory.

In the accompanying drawings:

Figure 1 is a side view of a projectile in accordance with my invention.

Figure 2 is a top view with a portion broken away for the purpose of illustration.

Figure 3 is a fragmentary view of one wing vane.

Figure 4 is an edge view.

Figure 5 is a face view of the opposite side thereof.

Figure 6 is a face view of another wing vane.

Figure 7 is an edge view.

Figure 8 is a reversed face view.

Figure 9 is a sectional detail view illustrating a pivotal mount for the vanes of one wing.

Figure 10 is a face view of a vane locking cap.

Figure 11 is a sectional detail view illustrating a vane stop, and

Figure 12 is a top view partly in section of a projectile provided with the distance increasing wings unfolded to carry the projectile an increased distance beyond ordinary projectiles.

In the embodiment of the invention selected for illustration, I make use of a projectile 10 provided with a diametrically opposed and longitudinal recesses 12 extending throughout the greater length of the projectile and opening through its circumferential face. A foldable wing 14 is mounted in each recess 12. Each wing comprises a leading and top vane 16 and a plurality of successively underlying vanes 18. All the vanes are similar in size and contour and converge uniformly toward the projectile. Normally the vanes 16 and 18 in each wing lie face to face and wholly inside their respective recess 12. The vanes in the two wings 14 are pivotally mounted on pins 20. Figures 3, 4 and 5 illustrate one of the vanes 18, this vane being provided with an eye head 22 provided with formations 24 on opposite sides thereof cooperating with the same formations on adjacent eye heads to provide a limited lost motion relationship between the vanes. This motion is such that the vanes may be pivoted relatively to each other for face to face nesting inside the recess, but the vanes are pivoted relatively to one another in opposite direction to spread in the manner of Figure 12, with the vanes overlapping

slightly so as to provide an unbroken wing surface.

One of the vanes 16 is illustrated in Figures 6, 7 and 8, this vane having an eye head 26 provided with a formation 28 coacting with one formation 24 on one of the vanes 18 to provide a lost motion connection so that the vane 16 has the same lost motion movement with respect to one of the vanes 18 as do the vanes 18 relatively to one another. An eye pin 30 is attached to the eye head 26.

Figure 9 illustrates the pivotal mount for one of the wings 14. The two wings are identical in construction and operation. The pin 20 is loosely receivable in the eye heads 22 and 26, which heads lie in face to face engagement. The bottom vane 18 lies on the wall face 32 of the recess 12. Four equally spaced openings 34 are provided in the eye head 26 for the reception of latch pins 36 attached to a latch cap 38 slidably mounted on the pin 20 but restrained from relative rotation by reason of a key 40 receivable in a groove 42 in the latch cap. These pins latch the eye head 26 against rotation when the vanes 16 and 18 are folded inside their recess 12, the formations 24 and 28 coacting so as to restrain all the vanes 16 and 18 from outward pivotal movement when lying in their recess 12 and with the pins 36 projected through the openings 34 in the eye head 26.

The pin 20 is threaded into the wall 32 of the recess, as at 44 and the pin is provided with a longitudinal bore 46 for a fuse 48 extending rearwardly of the projectile through an opening 50 for projection beyond its rear end 52 to be ignited when the projectile is fired.

In Figures 2 and 12 a tension spring 53 has one end connected with the eye bolt 30 and its other end secured to an anchor 54 attached to the projectile 10. This spring is of sufficient tension to pivot all the vanes 16 and 18 associated therewith to their unfolded position when the latch cap 38 is elevated sufficiently far to pull the pins 36 clear of the eye head 26. When the latch cap 38 is lifted off the eye head 26, the spring 53 imparts a rapid and forcible pivotal movement to the vane 16, with the result that the formations 24 and 28 cause the vanes 16 and 18 to fan outwardly to the wing formation of Figure 12, the bottom vane 18 being restrained from pivotal movement outside the recess 12 by reason of a lug 56 engageable with a stop 58 on the projectile.

Means for lifting the latch cap 38 to release the vanes, comprises an annular groove 60 in the face of the latch cap 38 engaging the eye head 26, which groove is filled with an explosive material

62 to be ignited by the burning fuse 48. As the material 62 explodes, the latch cap 38 is lifted off the eye head 26 to release the latter. The latch cap 38 is yieldingly biased against the eye head 26 by a compression spring 64, so that the eye head 26 will become latched to the latch cap 38 as the vane 16 is pivoted to its full open position in substantially right angular relation to the longitudinal axis of the projectile. An opening 66 is provided in the side of the pin 20 for reception of the fuse 48 to lead the latter into the explosive 62.

The recesses 12 lie in a horizontal plane positioned above the longitudinal axis of the projectile so as to more effectively balance the latter 15 when the wings are in their spread formations. Each wing structure is provided with a fuse, and the two fuses are timed through the length thereof to release the vanes only after the projectile has traveled a predetermined distance, with the 20 wings preferably opening as the projectile is at the highest point of its trajectory. Since the vanes are arranged in overlapping relationship and underlie one another rearwardly of the forward edges of their respective wings, the two 25 wings are characterized by bottom faces inclining rearwardly toward the axis of the projectile, so as to impart a lifting action to the projectile, thereby increasing the distance traveled by the projectile during the declining stretch of its trajectory.

Without further elaboration, the foregoing will

so fully explain my invention, that others may, by applying current knowledge, readily adapt the same for use under various conditions of service.

I claim:

1. The combination of a projectile body having recesses therein, foldable wings normally housed in said recesses, means for latching said wings in folded positions inside said recesses and in unfolded positions outside the recesses and the contour of the projectile, explosive means for actuating said first mentioned means to release the wings when in their folded positions, and means for projecting the wings to their unfolded positions.

2. The invention described in claim 1 wherein said wings each comprises a plurality of overlapping vanes, a pivot pin for each set of vanes, coating formations on the vanes in each set to limit the relative pivotal movement therebetween, in which said last mentioned means comprise springs respectively attached to one vane in each wing, said one vane in each wing being provided with openings, said first mentioned means including caps slidably mounted on the respective pins having lugs receivable in the openings in the said one vane of that pin, and in which said explosive means include explosive containing chambers located between said caps and the said one of said vanes and fuses leading into said explosive container chambers and through bores in the projectile to a position at the rear thereof.

STEPHEN A. MOORE.
